UNITED STATES PATENT OFFICE

2,506,688

WAR MEMORIAL FRAME

John Niver Scism, Baltimore, Md.

Application August 11, 1945, Serial No. 610,241

4 Claims. (Cl. 40—9)

1

This invention relates to display frames suitable for the framing of pictures or souvenirs.

More particularly, the invention relates to a display frame having the appearance of a helmet such as that worn by American soldiers during the Second World War.

One feature of the invention is to provide a frame, souvenir or memorial adapted to display a soldier's picture or some view relating to a soldier's travels or record, and which frame has the characteristics of a soldier's helmet.

Another feature of the invention relates to a relatively simple retaining device associated with a modified helmet and by means of which device a picture or other element to be displayed may be conveniently held in position transversely of an opening formed in the crown or top of the helmet.

The above and additional features and details are described and claimed in the following specification and claims and are illustrated in the accompanying drawing in which:

Fig. 1 shows a top plan view of a metal helmet which has been modified by forming an opening in the crown, the remaining portion of the helmet serving as a picture frame and the opening in the crown being adapted to display a picture or other souvenir positioned transversely to the side walls of the opening;

Fig. 2 is a side view of the helmet shown in Fig. 1;

Fig. 3 is a partial sectional view taken on the line 3—3 of Fig. 1, looking in the direction of the arrows, the retaining device being partially broken away whereby the relative position of the contents may be viewed;

Fig. 4 is an enlarged sectional view taken on the line 4—4 of Fig. 1, illustrating the manner of attachment and the retaining element and the positions of the several retained parts; and

Fig. 5 is a view in section of a modification of the flange member and fastening means.

Referring in detail to the several figures of the drawing, 1 is the top or crown of a helmet. 2 are the side walls. 3 is the lower edge or rim. 4 is an added name plate which may be desirable in connection with the helmet as a souvenir although not a part of the conventional military helmet.

In the manufacture of the product of this invention, it is expedient to use the usual helmet of the type used by American soldiers during the Second World War. However, any type of helmet will suffice, provided its contours are such that the following treatment may be given it.

2

If not already relatively flat on the upper surface, the major portion of the upper surface is first flattened. Then an opening is formed by cutting away the top, to provide a hole through the top, as shown. This opening has the shape of an oval, merely to conform to the general configuration of the helmet. Manifestly the invention is not based on the particular shape of the opening.

The marginal edges of the top adjacent the opening are pushed inwardly, providing a flange 5 which extends substantially at right angles to the flattened portion of the top and in the same general direction in which the sides of the helmet extend.

15 The innermost portion of the flange 5 is bent substantially at right angles and thus transversely of the opening to provide a ledge 6, the purpose for which will be further explained. The innermost edge of the ledge 6 is indicated at 7 and it conforms to the shape of the opening in the top of the helmet.

16 Along the width of the flange 5 between the top of the helmet 1 and the ledge 6 is formed an outwardly extending annular rib 8 which 20 helps serve as a detent for the member which holds the display material, as will be described.

25 Means for holding the display material includes a cap-like member 9 which engages and is secured to the flange 5. The element 9 includes a wall transverse to the flange 5 and is provided with a side wall 10 which is adapted to engage and snugly fit over the outer surface of the flange 5. The wall 10 is serrated to provide a plurality of fingers which grip the sides of the flange 5. Along the length of the fingers of the wall 10 is an outwardly extending rib 11 on the inner surface of which is a corresponding groove. The groove is adapted to receive, with a spring-held effect, the rib 8 on the flange 5. This construction serves to enable the fingers of the wall 30 10 to be snapped over the rib 11 and the element 9 thus to be frictionally secured to the flange 5 when the parts are assembled. Similar movement in the reverse direction enables these parts to be disengaged.

40 Assuming that the helmet type of frame is to be used for displaying a picture, and with reference to Figs. 3 and 4, it may be noted that the following parts are positioned within the retaining member 9. 12 is a pad or innermost panel adapted to cover the inner area and can be positioned next adjacent the inside face of the member 9. The pad 12 supports the picture. The next element may be a picture 13 45 which rests against the pad 12. Positioned mar-

ginally within the retaining member 9 and resting over the margin of the picture is a mat 14 which serves the usual function of outlining the picture to be displayed. In this instance, the mat rests against the underface of the ledge 6 and serves to protect the marginal portion of the picture from damage by contact with the underface of the ledge 6. Obviously also the mat 14 can provide an artistic effect better than the edge 7 of a metal flange. When held in this position, as shown in Figs. 3 and 4, the display material is in alignment with the opening bounded by the flange 5 and also extends transversely across that opening.

Referring to Fig. 5, it will be noted that this is a sectional view similar to Fig. 4 but showing certain different details of construction, as will be described. The structure shown in Fig. 5 does not include the ledge 6, such as shown in Figs. 3 and 4. As result, the mat 14 rests directly against the end edge of the flange 5 and the width of the metal of the flange 5 serves the same function as the ledge 6 of Figs. 3 and 4. In other words, the retaining member 9 holds the displayed object and the mat 14 directly against the end edge of the flange 5. Fig. 5 is distinctive also in that the securing means relies on the frictional contact between the serrated fingers of the wall 10, the rib 8 on the flange 5 and the corresponding rib 11 and its groove in the wall 10 being eliminated.

Means for assisting in the mounting or use of the helmet is provided by brackets 15 located at opposite sides of the helmet and on the inner walls thereof. One arm of each bracket may be welded or soldered or otherwise fastened to the wall of the helmet. Each bracket is provided with a hole 16 through which straps or other fastening means may extend.

The space between the lines 17 and 18 on Fig. 1 comprising a peripheral border-like space adjacent the display opening of the frame is intended for the reception of lettering and description relating to the subject matter of the memorial or picture or other article displayed in the frame. The lines may be painted on the helmet or lightly scored and the lines are not intended to have a substantial depth but are merely intended to designate a space suitable for the reception of lettering.

I claim:

1. A display frame of the general contour of a helmet comprising a top and sides, the top having an opening therethrough, the material of the top at the margin of said opening extending from the top inwardly in substantially the same direction as said sides, and constituting an inwardly projecting flange defining an opening in alignment with the opening in said top, and a retaining element detachably and frictionally secured to the exterior of said flange and having a transverse portion extending across the opening defined by said flange, said retaining element being adapted to hold display material between its transverse portion and said flange and in alignment with and transversely to said opening.

2. A display frame of the general contour of a helmet comprising a top and sides, the top having an opening therethrough, the material of the top at the margin of said opening extending from the top inwardly in substantially the same di-

rection as said sides, and constituting an inwardly projecting flange defining an opening in alignment with the opening in said top, the material of said inwardly projecting flange at its innermost end and farthest from said top being extended centrally and transversely to said inwardly projecting flange and providing a second and narrow flange extending part way only across said opening, and a retaining element detachably and frictionally secured to the exterior of said inwardly extending flange and between the latter and the sides of said helmet and having a transverse portion extending substantially opposite said second flange and extending in a plane parallel to the plane in which said second flange lies, said retaining element being adapted to hold display material between its transverse portion and said second flange and in alignment with and transversely to said opening.

3. A display frame of the general contour of a helmet comprising a top and sides, the top having an opening therethrough, the material of the top at the margin of said opening extending from the top inwardly in substantially the same direction as said sides, and constituting an inwardly projecting flange defining an opening in alignment with the opening in said top, and a retaining element detachably and frictionally secured to the exterior of said flange and between said sides and said inwardly projecting flange and having a transverse portion extending across the opening defined by said flange, said retaining element being adapted to hold display material between its transverse portion and said flange and in alignment with and transversely to said opening.

4. A display frame comprising a metal ring having an advance and forward face and sides extending rearwardly from said forward face, said forward face having an opening therethrough the margin of which is spaced from said sides, the material of said forward face at the margin of said opening extending from said forward face inwardly in substantially the same direction as said sides, and constituting an inwardly projecting flange defining an opening in alignment with the opening in said forward face, and a retaining element detachably and frictionally secured to the exterior of said flange and between said sides and said inwardly projecting flange and having a transverse portion extending across the opening defined by said flange, said retaining element being adapted to hold display material between its transverse portion and said flange and in alignment with and transversely to said opening.
